UNITED STATES PATENT OFFICE.

GEORGE WALKER, OF NEW YORK, N. Y.

WOOD-DISTILLING APPARATUS.

No. 904,165.

Specification of Letters Patent. Patented Nov. 17, 1908.

Application filed May 29, 1908. Serial No. 435,848.

To all whom it may concern:

Be it known that I, GEORGE WALKER, a citizen of the United States, residing at New York, in the county of New York and State of New York, have invented certain new and useful Improvements in Wood-Distilling Apparatus, whereof the following is a full, clear, and exact specification.

This invention relates to wood distilling apparatus; and comprises a wood distilling retort and setting mutually related to permit a good circulation of heat around said retort while also providing for expansion and contraction and also comprises certain improved details of said retort and setting; all as more fully hereinafter set forth and as claimed.

In what is known as the retort process of distilling wood and other vegetable materials to obtain valuable products therefrom, the wood is placed in a retort and gradually heated by fire heat until it loses water vapor and accompanying volatile bodies and then undergoes pyrolytic decomposition or what is known as "destructive distillation," yielding acetic and other acids, creosote, methyl alcohol, acetone, "methyl acetone," tar and tar oils and many other products, together with considerable amounts of combustible gas. In the case of coniferous woods, the steam first evolved is accompanied by turpentine and in the subsequent pyrolysis, the contained rosin and resins yield rosin oils, etc. After the destructive distillation is completed, the residue in the retort is charcoal. The combustible gas and part of the charcoal are used for heating the retort in subsequent operations.

In the stated operation, the retort is exposed to a wide range of temperatures, beginning cold and running up to temperatures in the neighborhood of a red heat, and while it is desirable of course to provide a good circulation of flame gases about the retort to give evenness of heating yet the great expansion and contraction which the retort undergoes prevent the usual arrangement of brickwork flues employed with boilers and the like. It is not advisable to set such a retort snugly against a masonry wall at any point.

It is one of the objects of the present invention to provide a setting which will give such circulation while providing for expansion and contraction and it is a further object to provide for an even, well distributed heat by means coöperating with the circula-

tory means. To this end, the retort, which may have the form of a simple cylinder, is laterally provided with T or L iron flanges affixed thereto while the masonry setting is provided with projecting plates upon which such flanges are slidably supported. Flanges and plates together form a flue septum extending the length of the retort and giving a fire flue above such septum and another below the same, both flues operating to heat the retort. The lateral flanges resting slidably on the plates, expansion and contraction are provided for. The retort body may advantageously be constructed of a sheet of boiler plate, of, say, $\frac{3}{8}$ inch iron or steel, bent into a cylinder with the plate edges in abutting contact. A piece of T or L iron with the head riveted or otherwise secured to the plate on either side of the abutting contact serves at once to close the joint and to furnish one of the described flanges while a similar strip riveted to the cylinder on a line diametrically opposite furnishes the other flange.

In use, wood retorts tend to burn through on the side next the firing means, and particularly if direct impingement of flame be permitted, and the described type of retort is especially useful for this reason since the top and bottom can be easily reversed when the latter begins to burn through, thereby adding materially to the life of the retort. Being cylindrical, the top and bottom are alike, and the flanges being diametrically opposite function equally well in either position of the retort. It is of course necessary that the vapors be led off from a point above the bottom in either position of the retort and in the embodiment here preferred, this result is secured by providing the end wall of the cylinder with a pair of openings adapted to engage a vapor conduit, the lower one in either position of the retort being capped.

It being desirable, as stated to spare the retort the direct impingement of flame, below the retort there is provided a masonry arch extending its full length and provided with ports giving communication between the firing means and the flue formed between the retort, the angle irons and said arch, these ports being set at intervals along the length of the arch and passing therethrough in a direction more or less tangential to the retort walls. This prevents flame coming into direct contact with the retort bottom. The firing means may be an ordi-

nary grate and in addition thereto gas burners for utilizing the stated combustible gases. These burners should be set in pairs in such manner that the flames from each pair will 5 mutually impinge upon each other, giving a "baffled flame," and further preventing flame impingement on the retort bottom.

In the accompanying illustration I have shown, more or less diagrammatically, a 10 wood distilling apparatus according to the present invention embodying the stated improvements as well as others, to be more specifically described hereinafter.

In this showing Figure 1 is a view, partly 15 in elevation and partly in transverse vertical section, of a bank of retorts (four are shown) and their setting; Fig. 2 is a vertical longitudinal section of a single retort and its setting; Fig. 3 is a diagrammatic plan 20 view of a bank of retorts and attached condenser; Fig. 4 is a similar view of a double bank of retorts and condenser; and Figs. 5, 6 and 7 are detail views of the closure for the fore end of the retort.

Referring first to Fig. 1, A, B, C and D 25 are four similar retorts, A being shown with door 1 in place. Each retort is made of a sheet 2 of boiler iron bent into a cylinder with edges abutting and joining at 3. Over 30 this joint is secured a piece of angle iron 4 (shown as an L iron), which closes the joint and provides a projecting lateral flange 5. On the opposite side of the retort is a similar angle iron 6, providing another projecting flange. Each retort is mounted in a masonry housing 7, with a dividing wall 8 between each pair of retorts. Through this wall extends a plate 9, a similar plate being 35 in the end wall 10 of the housing, and on these plates the flanges rest slidably. Flanges and plates together form flue septa 40 extending longitudinally of the retorts and dividing the inclosing chamber into upper and lower flues 11 and 12. At the fore and 45 rear ends (see Fig. 2), the retorts rest on rollers 13, supported on plates 14, thus providing for longitudinal expansion.

Below each retort is a fire chamber 15, mounted by an arch 16, perforated with 50 ports 17, set tangentially to the retort walls above. Double firing means are provided, consisting of grate 18 and double opposing gas burners 19, fed by pipes 20 extending backward to gas main 21, common to the 55 bank of retorts. The flames from these burners meet and oppose, producing perfect combustion in the fire chamber and sending well mixed flame gases upward through the tangential ports along the walls of the retort without production of a flame impinging on the bottom thereof. The hot gases pass backwards along the bottom of the retort below the described flue septa to rear flue 22 behind the retort and thence forward above the flue septa to cross flue 23, common to the

whole bank, the exit being controlled by damper 24, and thence to exit through stack 25.

Each retort is provided (see Fig. 2) with an axial pipe 26 communicating with steam main 27 common to the bank. Being axial 70 this pipe does not prevent the described reversal of the retort. This pipe permits the introduction of steam to aid in the distillation, if desired. Each retort is further provided with a vapor pipe 28, tapped into its 75 upper portion. These pipes communicate with vapor main 29, common to the bank. The rear end of the retort, is further provided with a blank and capped perforation 80 so that when the bottom of the retort becomes burned in use the retort may have its top and bottom reversed, the vapor pipe now entering through 30 and the perforation through which it formerly communicated being capped. The flanges of the angle 85 irons of course act equally well as flue septa and supports in either position of the retort. This expedient adds materially to the life of the retort.

To provide a closure for the front end of 90 the retort, adaptable for use in either position of said retort, an iron ring 31 is secured thereto, as by rivets 32. This ring extends somewhat beyond the end of the described cylinder and carries a V-ed groove 33, containing packing material 34 (shown as asbestos rope), on its forward face (see Fig. 5). This ring further carries pairs of depending lugs 35, through which is passed a pivot 36. Mounted on this is a swinging 100 bolt 37, carrying nut 38. The door (1) is provided with corresponding slots 39 (see Fig. 1 and Fig. 5), into which the bolts pass, permitting the nut to engage the door. The door is provided with a rounded annular 105 flange 40 engaging the packing in the groove (33). By the described means the door can be made to give an easily engaged and disengaged gas-tight closure in either position of the retort.

To provide for removing the door in filling and emptying the retort, the door has a ring or similar device 41 at the top, engaging a hook 42 carried by a turnbuckle 43 depending from trolley wheel 44 running on a 115 rail 45 above the retort. By disengaging the nuts on the swinging bolts, the door can be run forward away from the retort and out of the way, leaving the mouth of the retort open and free.

In practice, two banks of retorts, each having five retorts, are usually mounted back to back (see Fig. 4) with separate condensers mounted in a common condenser tank 46, supplied with water through inlet 47 and emptied through outlet 48. In Fig. 3, a single bank of retorts is shown with an individual condenser tank. The condenser is formed of a plurality of pipe sections supported in the tank; as shown of four sec- 125

tions, respectively 49, 50, 51 and 52. Section 49 communicates at its forward end with the vapor main through connection 53, at its rear end with 50 while 50 at its other end 5 communicates with 51, and 51 at its rear end with 52. The forward end of 51 has a connection 54 leading to collecting tanks and gas withdrawal means (not shown). Each successive section is smaller in diameter. If 10 the vapor main be a 12 inch pipe, the first condenser section may be 10 inch, the second, 8 inch, the third, 6 inch and the fourth 4 inch. These sections may be laid in substantially the same plane, or with but little 15 inclination, the diminution in size causing condensates to feed forward from one section into another.

The described wood distilling apparatus may of course be employed with any kind of 20 wood, whether hardwood or coniferous wood, or with any kind of vegetable or other matter yielding valuable products upon distillation. The described firing means in combination with the tangentially perforated arch 16 and the type of circulation provided by the flanged flue septa insure an even, well distributed heating of the retort and contents, preventing any localized overheating which will be detrimental to the 25 retort, or to the distillation operation, and much retarding the burning of the bottom of said retort. And when such burning does begin to take place, the retort may, as stated, be simply reversed, top for bottom. The 30 steam pipe shown materially aids in controlling temperatures and keeping them below a dangerous point, and particularly in the first part of the distillation. In distilling resinous woods, such as coniferous woods, 35 generally yield considerable turpentine in the first part of the distillation before true destructive distillation set in, and introduction of some steam is here useful.

Firing may be either by the grate or by 40 the gas burners, or, and usually, by both, the preliminary heating being by fuel, such as charcoal, on the grate and gas being sent to the burners when it begins to pass through the condensers in the further heating to produce destructive distillation. The combustible gas from the condensers may of course be stored and used for the preliminary heating, or the gas from one bank of retorts 45 may be used to heat the other.

55 What I claim is:—

1. A wood distilling apparatus comprising a reversible cylindrical retort carrying diametrically opposite lateral supporting flanges, a surrounding heating chamber, longitudinal projecting plates mounted in the wall of such chamber on which such flanges are slidably supported; flanges and plates co-operating to form flue septa in such chamber, a flue at the back of such retort establishing communication between the upper

and lower flues formed by such septa, means for withdrawing waste gases from the upper flue and means for furnishing flame gases to the lower flue.

2. A wood distilling apparatus comprising 70 a reversible cylindrical retort having a body of sheet metal bent in cylindrical form with meeting edges, a strip of angle iron secured to the body over such meeting edges to close the joint and form a lateral supporting flange, a strip of angle iron secured to the opposite side of such body to form a corresponding flange, a heating chamber surrounding such retort, longitudinal projecting plates mounted in the walls of such 75 chamber on which such flanges are slidably supported, such flanges and plates co-operating 80 to form flue septa dividing such heating chamber into upper and lower flues, a vertical flue at the back of such retort establishing 85 communication between such upper and lower flues, means for withdrawing waste gases from the upper flue and means for furnishing flame gases to the lower flue.

3. A wood distilling apparatus comprising 90 a reversible cylindrical retort carrying lateral supporting flanges, a surrounding heating chamber, longitudinal projecting plates mounted in the walls of such chamber on which such flanges are slidably supported, such flanges and plates co-operating 95 to form flue septa dividing such heating chamber into upper and lower flues, means for withdrawing waste gases from the upper flue, a lower wall for the lower flue carrying 100 perforations therethrough tangential to the walls of said retort, and firing means below such lower wall.

4. In a wood distilling apparatus, a reversible retort comprising a body of sheet 105 metal curved into cylindrical shape with meeting edges, an angle iron strip secured over such meeting edges to close the joint and afford a supporting lateral projecting flange and another angle iron strip secured 110 to the diametrically opposite side of said body to afford a corresponding lateral projecting flange.

5. A wood distilling apparatus comprising 115 a reversible cylindrical retort provided with two diametrically opposite lateral flanges, a heating chamber surrounding said retort and having a projecting lateral member opposite each such flange on which such flanges are slidably supported and means 120 for furnishing heat to such chamber.

6. A wood distilling apparatus comprising 125 a reversible cylindrical retort provided with two diametrically opposite lateral flanges, a heating chamber surrounding such retort and extending back of the same, continuous projecting lateral members in the wall of such chamber opposite such flanges, slidably supporting the same and co-operating therewith to form flue septa dividing 130

such flame chamber into upper and lower flues communicating back of such retort, means for withdrawing waste gases from the upper flue and means for furnishing heating gases to the lower flue.

7. A wood distilling apparatus comprising a cylindrical retort, a surrounding heating chamber, longitudinal flue septa dividing such chamber into upper and lower flues, 10 a vertical flue establishing communication between such flues back of the retort, a perforated lower wall for the lower flue having its perforations tangential to the cylindrical walls of the retort and firing means below 15 such perforated wall.

8. In a wood distilling apparatus, a reversible retort comprising a cylindrical body of sheet metal, means for supporting such body with either side up, a rear closure for 20 such body, a metal ring surrounding the mouth of such body and provided with a circumferential series of swinging bolts and a non-reversible door provided with a corresponding circumferential series of slots 25 adapted to engage such swinging bolts.

9. In a wood distilling apparatus, a reversible horizontal cylindrical retort, a non-reversible vertical door adapted to be clamped to the mouth of such retort in either position 30 thereof, a rail extending outward above such door and traversing means upon such rail engaging such door.

10. In a wood distilling apparatus, a reversible horizontal cylindrical retort having 35 lateral flanges for supporting the same in a heating chamber, said retort being provided with an axial steam pipe and having two perforations near opposite sides of said retort, one such perforation carrying a vapor 40 delivery pipe and the other perforation being capped.

11. In a wood distilling apparatus, a horizontal cylindrical retort, a heating chamber surrounding the same and gas firing means 45 communicating with such chamber at points removed from the bottom of said retort, said gas firing means comprising a fire chamber provided with pairs of opposite gas burners and said gas burners being set to produce 50 meeting flames, whereby combustion is substantially completed in said fire chamber

prior to entry of the flame gases to said heating chamber.

12. In a wood distilling apparatus, a reversible cylindrical retort mounted in a 55 housing and spaced apart therefrom to form an annular heating chamber around said retort, lateral supporting flanges on said retort slidably supported on said housing and operating to support the retort and divide 60 such heating chamber into upper and lower flues, means for withdrawing waste fire gases from the upper flue, means for establishing communication between upper and lower flues and means for supplying flame gases to 65 the lower flue in a direction tangential to the walls of the retort.

13. In a wood distilling apparatus, a reversible cylindrical retort, a clamping door for the mouth of said retort, a doubly perforated wall for the rear end of said retort, one perforation carrying a vapor pipe and the other being capped, an axial steam pipe entering through said wall, diametrically opposite lateral flanges on the said retort, 75 a heating chamber surrounding the retort, means on the walls of such chamber for slidably supporting such flanges and means for furnishing heating gases to said heating chamber.

14. In a wood distilling apparatus, a reversible cylindrical retort, horizontally mounted in an annular heating chamber on a yielding lateral support along its median line on either side, such support dividing 85 such heating chamber into semi-annuli above and below the retort and communicating at its rear, a fire chamber below the heating chamber and structurally separate therefrom, gas-firing means in such fire chamber 90 adapted to produce a substantially complete combustion of gas therein, and means for delivering the products of combustion from the fire chamber into the lower semi-annulus of the heating chamber at a point removed 95 from the bottom of the retort.

In testimony whereof, I affix my signature in the presence of two subscribing witnesses.

GEORGE WALKER.
